UNITED STATES PATENT OFFICE.

HENRY P. SINCLAIRE, OF CORNING, NEW YORK.

DESIGN FOR A DISH.

47,412.

Specification for Design.

Patented June 1, 1915.

Application filed February 23, 1915. Serial No. 10,140. Term of patent 14 years.

To all whom it may concern:

Be it known that I, HENRY P. SINCLAIRE, a citizen of the United States, and a resident of Corning, in the county of Steuben and State of New York, have invented a new, original, and ornamental Design for a Dish, of which the following is a specification, reference being had to the accompanying drawing, in which—

I claim:

The ornamental design for a dish substantially as shown.

The foregoing specification signed at Corning, New York, this 12th day of February, 1915.

HENRY P. SINCLAIRE.

In presence of—

MARVIN OLcott,
B. F. ROBINSON.
